DESIGN.

S. BRAUNSTEIN.

PORTABLE LAMP.

APPLICATION FILED JUNE 14, 1917.

51,197.

Patented Aug. 28, 1917.

UNITED STATES PATENT OFFICE.

SIMON BRAUNSTEIN, OF NEW YORK, N. Y.

DESIGN FOR A PORTABLE LAMP.

51,197.

Specification for Design.

Patented Aug. 28, 1917.

Application filed June 14, 1917. Serial No. 174,774. Term of patent 3½ years.

To all whom it may concern:

Be it known that I, SIMON BRAUNSTEIN, a citizen of the United States, residing at New York city, in the county of New York and State of New York, have invented a new, original, and ornamental Design for a Portable Lamp, of which the following is a specification, reference being had to the accompanying drawing, forming part thereof.

The drawing is a side elevation of a portable lamp showing my new design.

I claim as my invention:

The ornamental design for a portable lamp, substantially as shown.

Signed at New York city, in the county and State of New York, this 12th day of June, 1917.

SIMON BRAUNSTEIN.
